UNITED STATES PATENT OFFICE.

ALBERT F. FULLER, OF NEWARK, NEW JERSEY, ASSIGNOR TO THE J. E. MERGOTT COMPANY, A CORPORATION OF NEW JERSEY.

PURSE OR BAG FRAME.

SPECIFICATION forming part of Letters Patent No. 688,992, dated December 17, 1901.

Application filed April 20, 1901. Serial No. 56,681. (No model.)

To all whom it may concern:

Be it known that I, ALBERT F. FULLER, a citizen of the United States, residing at Newark, in the county of Essex and State of New Jersey, have invented certain new and useful Improvements in Purse or Bag Frames; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 This invention relates generally to improvements in purse or bag frames, and more particularly to a novel construction of locking device or holding-catch combined with a marginal top bead suitably secured upon one of the frame-sections and arranged to overlap the joint of the two frame-sections of the purse or bag frame when closed.

This invention therefore has for its primary object to provide a neat, strong, and simple 25 construction of purse or bag frame combining with its hinged or pivoted frame-sections a marginal bead suitably secured in its position upon one of the said frame-sections and having a locking or holding catch mechanism placed in its inner chambered part, the 30 said catch mechanism being provided with an upwardly-extending finger-piece which projects through a slot or opening in the upper part of the said marginal or edge strip for the 35 manipulation of the same and the opening of the two bag-frame sections.

By means of my novel construction and arrangements of the various parts hereinafter more particularly described the employment 40 of an extra lock casing or box for the holding-catch mechanism is dispensed with, and the cost of construction of this class of bag-frames is thereby greatly reduced.

This invention therefore consists in the 45 novel construction of purse or bag frame and holding-catch combined with the marginal or edge bead of the frame-sections, all of which will be hereinafter more fully described and then finally embodied in the various clauses 50 of the claim.

The invention is fully illustrated in the accompanying drawings, in which—

Figure 1 is a front or face view of the purse or bag frame, its marginal bead or edge strip, and the holding or locking catch, which embodies 55 in its construction the principal features of this invention; and Fig. 2 is a top view of the same. Fig. 3 is a bottom view of the two frame-sections, the same being represented in their open relation and said view showing, in connection with the said frame-sections, one arrangement of fastening-lugs for securing the marginal or edge strip or bead to one of the said frame-sections and said view also illustrating with the one frame-section a portion 60 of the under side of the holding or locking catch. Fig. 4 is a vertical cross-section, on an enlarged scale, of the two frame-sections, the marginal or edge strip or bead, and the holding-catch mechanism, all represented in 65 their holding or locked engagement with the parts of the closed frame-sections, said vertical section being taken centrally across the closed frame-sections and the catch mechanism. Fig. 5 is a similar cross-section of the 70 several parts represented in said Fig. 4, but illustrating the lock-catch mechanism in its operated position to permit of the separation or open relation of the two frame-sections, both of said sectional views being represented 75 as taken on a line 44 in Fig. 3. Fig. 6 is a vertical cross-section, on an enlarged scale, taken on line 66 in said Fig. 3, said view representing the two frame-sections in their closed relation and the bead or edge strip provided with 80 an inwardly-turned supporting-lug, on which the holding-catch mechanism is placed and supported in its position in said edge or bead strip. Fig. 7 is a vertical cross-section taken on line 77 in said Fig. 3, representing one manner of securing the marginal edge or bead 85 strip in its fixed position upon one of the said frame-sections and overlapping the joint formed by the two frame-sections when in their closed relation. Fig. 8 is a longitudinal 90 vertical section of a portion of the edge or bead strip and a portion of the one frame-section with which it is connected, the said view also illustrating in elevation the arrangement of the holding-catch mechanism 95 100

in said edge or bead strip, with the finger-piece of the catch projecting through a slot or opening in the top of said edge or bead strip. Fig. 9 is a blank representation of a piece of metal from which the catch device is struck up, and Figs. 10 and 11 are two perspective views of the said catch as it appears when finished. Fig. 12 is a perspective view of a portion of the edge or bead strip employed with the frame-sections, illustrating the general arrangement of the holding-lugs for securing the bead upon the one frame-section and also the inwardly-turned supporting-lugs on which the holding-catch plate represented in said Figs. 10 and 11 is placed. Fig. 13 is a perspective view of one form of spring used with the holding-catch.

Similar characters of reference are employed in all of the said above-described views to indicate corresponding parts.

In the several figures of the drawings, 1 and 2 indicate the two frame-sections, the said frame-sections being of any suitable shape and form and being of the usual Ω -shaped cross-section, as shown. The said frame-sections 1 and 2 are each provided with the downwardly-extending parts 3, which terminate in the flat ends or ears 4, provided with the usual holes or perforations for the reception of the pivotal pins 5 to provide the hinge-joint of the said two frame-sections 1 and 2. Secured upon the outer surface of one of the said frame-sections, as 2, is an ornamental marginal bead or edge strip 6, the said strip also being made Ω -shaped in cross-section; but of course it will be understood that the said strip may be of any other desirable configuration in its cross-section. The said bead or edge strip 6 is formed with the downwardly-extending end portions 7 and is also provided with suitably-arranged and suitably-constructed holding-lugs 8, which are passed through correspondingly-placed perforations or slits 9 in the said frame-section 2, and are then bent over against the under and inner surface of the said frame-section 2, as clearly indicated in the several figures of the drawings. The downwardly-extending end portions 7 of the bead or edge strip are arranged along the outer surfaces of the downwardly-extending parts 3 of the frame-section 2, as shown, and the extreme lower ends of the portions 7 are held in their fixed positions by the said pins 5, forming the pintles of the hinge-joint of the bag-frame. The said bead or edge strip 6 is also provided in one of its sides, as will be seen from an inspection of Fig. 12, with one or more openings or cut-away parts 10, and in its other side said strap is provided with a pair of inwardly-extending supporting-lugs 11. The said bead or edge strip is also provided in its upper surface with a longitudinally-extending slot or opening 14. When the said edge or bead strip 6 is secured in its fixed position upon the said frame-section 2, then a portion of the said strip 6 will project beyond the one

side of the said frame-section 2, and when the frame-section 1 is closed against the section 2 it will be brought directly beneath the said overhanging part of the bead or edge strip and the joint between the two frame-sections will be fully closed. Within the chambered part of the said bead or edge strip 6, resting directly upon the inwardly-extending supporting-lugs 11 and directly beneath the longitudinal slot or opening 14, is the holding-catch mechanism for retaining the two frame-sections 1 and 2 in their closed relation when they are brought together. This lock mechanism consists, essentially, of a suitable catch-plate 15, which is made from a blank of sheet metal, as 16. (See Fig. 9 of the drawings.) The said blank is formed with a forwardly-extending member 17' and with the rearwardly-extending member 18' and end 20', which is separated from the member 18' by the incisions 19'. The said blank 16 is also provided with a pair of oppositely and laterally extending members 21, each of which is provided with the projections 22' and 23'. The said blank is also provided with an opening or slot 24 and a pair of perforations 25 for the purposes to be presently described.

The several members of the blank 16 are bent into the various shapes and positions indicated in Figs. 10 and 11, the member 17' being bent in a downward direction and at a right angle, or approximately so, to the body of said plate to form a holding-catch 17. The said rearwardly-extending member 18' is bent in a line in alignment with the longitudinally-placed slot or opening 24 in such a manner to provide the upwardly-inclining arm 18 and then bent in an upward direction to form the vertically-arranged finger-piece member 19. The extreme free end portion 20' of this member is then bent in a downward direction and tightly closed down against the face of the member 19, as at 20, whereby a strong and serviceable finger-piece is formed of a double thickness of metal, as will be clearly seen from an inspection of Figs. 4, 5, and 10. A spring 26 is then placed upon the supporting portions 23, formed by the projections 23, hereinabove mentioned, the said spring being held in position by the loops 22, which are formed by the members 22' being bent around the parts 28 of the said spring. The said spring is also provided with an angular portion 27, which is inserted in the slot 24, so as to hold the spring in its operative position upon the said supporting portions 23 of the catch-plate against turning when the catch-plate is arranged in its place in the chambered part of the bead or edge strip 6. The said spring 26 is further provided at its ends with right-angled end pieces or arms 29, which when the said spring has been secured in its operative position upon the said catch-plate 130 extend in an upward direction from the upper surfaces of the side members 21 of the said plate, as clearly illustrated in Fig. 10. This catch-plate is placed within the cham-

bered portion of the said bead or edge strip 6 so as to rest directly upon the inwardly-projecting supporting lugs or members 11, with the finger-piece of the catch-plate extending into and projecting through the longitudinally-arranged slot or opening 14 in the said bead or edge strip, as clearly illustrated in Figs. 4, 5, and 8. At the same time the free ends of the upwardly-extending end 10 pieces or arms 29 of the spring 26 will bear firmly against the inner surface of the said bead or edge strip, as shown, whereby the said catch-plate 15 is securely retained in its position upon the supporting-lugs 11, and the 15 downwardly-extending holding-catch 17 of the said plate can be readily forced over suitable holding-lugs 30 in the frame-section 1 when the latter frame-section is closed against the frame-section 2, the said holding-lugs 30 20 also partly extending into the holes 25 in the catch-plate 15, all of which is clearly illustrated in said Fig. 4 of the drawings.

To separate the frame-sections 1 and 2 when it is desired to open the mouth of the bag or 25 purse, all that is necessary is to push the finger-piece of the catch device in the direction of the arrow *x* in Fig. 5, whereby the holding-catch 17 can be withdrawn from its engaged position with the straight edges of the holding-lugs 30 upon the frame-section 1, and the 30 two frame-sections can then be separated, as will be clearly understood.

I am aware that changes may be made in the several arrangements and combinations 35 of the various parts, as well as in the details of the construction thereof, without departing from the scope of this invention. Hence I do not limit my invention to the exact arrangements and combinations of the parts as 40 herein described, and illustrated in the drawings, nor do I confine myself to the exact details of the construction of the said parts.

Having thus described my invention, what I claim is—

45 1. In a purse or bag frame, the combination, with a pair of frame-sections, and a chambered bead-strip on one of said frame-sections, said strip having a longitudinally-extending and centrally-disposed slot in its upper surface, of 50 a holding-catch mechanism in the chamber of said strip, and an upwardly-projecting finger-piece on said mechanism extending into and projecting, normally, vertically from said slot and directly above the central portion of the 55 said strip in alignment with the central longitudinal axis of said strip, substantially as and for the purposes set forth.

2. In a purse or bag frame, the combination, 60 with a pair of frame-sections, and a chambered bead-strip on one of said frame-sections, said strip having a longitudinally-extending and centrally-disposed slot in its upper surface, of a holding-catch mechanism in the chamber of said strip, and an upwardly-projecting finger-piece 65 on said mechanism extending into and projecting, normally, vertically from said slot and directly above the central portion of the

said strip in alignment with the central longitudinal axis of said strip, said catch mechanism, comprising, a spring-actuated catch-plate and a holding-catch 17, and holding-lugs on the other frame-section adapted to be brought in holding engagement with said catch 17, substantially as and for the purposes set forth. 75

3. In a purse or bag frame, the combination, with a pair of frame-sections, and a chambered bead-strip on one of said frame-sections, said strip having a longitudinally-extending and centrally-disposed slot in its upper surface, 80 and inwardly-extending supporting-lugs connected with said strip, of a holding-catch mechanism supported on said supporting-lugs and an upwardly-projecting finger-piece on said mechanism extending into and projecting, normally, vertically through and from the slot and directly above the central portion of the said strip in alignment with the central longitudinal axis of said strip, substantially as and for the purposes set forth. 90

4. In a purse or bag frame, the combination, with a pair of frame-sections, and a chambered bead-strip on one of said frame-sections, said strip having a longitudinally-extending and centrally-disposed slot in its upper surface, 95 and inwardly-extending supporting-lugs connected with said strip, of a holding-catch mechanism supported on said supporting-lugs and an upwardly-projecting finger-piece on said mechanism extending into and projecting, normally, vertically through and from the slot and directly above the central portion of the said strip in alignment with the central longitudinal axis of said strip, said catch mechanism, comprising a spring-actuated 105 catch-plate and a holding-catch 17, and holding-lugs on the other frame-section adapted to be brought in holding engagement with said catch 17, substantially as and for the purposes set forth. 110

5. In a purse or bag frame, the combination, with a pair of frame-sections 1 and 2, said section 2 having lug-receiving holes, of a chambered bead-strip provided with lugs 8 arranged in said holes in the frame-section 2 115 and bent over against the under surface of said frame-section, said strip having a longitudinally-extending and centrally-disposed slot in its upper surface, of a holding-catch mechanism in the chamber of said strip, and 120 an upwardly-projecting finger-piece on said mechanism extending into and projecting, normally, vertically through and from the slot and directly above the central portion of the said strip in alignment with the central 125 longitudinal axis of said strip, substantially as and for the purposes set forth.

6. In a purse or bag frame, the combination, with a pair of frame-sections 1 and 2, said section 2 having lug-receiving holes, of a chambered bead-strip provided with lugs 8 arranged in said holes in the frame-section 2 130 and bent over against the under surface of said frame-section, said strip having a longi-

- itudinally-extending and centrally-disposed slot in its upper surface, of a holding-catch mechanism in the chamber of said strip, and an upwardly-projecting finger-piece on said mechanism extending into and projecting, normally, vertically through and from the slot and directly above the central portion of the said strip in alignment with the central longitudinal axis of said strip, said catch mechanism comprising, a spring-actuated catch-plate and a holding-catch 17, and holding-lugs on the other frame-section 1 adapted to be brought in holding engagement with said catch 17, substantially as and for the purposes set forth. 5
7. In a purse or bag frame, the combination, with a pair of frame-sections 1 and 2, said section 2 having lug-receiving holes, of a chambered bead-strip provided with lugs 8 arranged in said holes in the frame-section 2 and bent over against the under surface of said frame-section, said strip having a longitudinally-extending and centrally-disposed slot in its upper surface, and inwardly-extending supporting-lugs connected with said strip, a holding-catch mechanism supported on said supporting-lugs, and an upwardly-projecting finger-piece on said mechanism extending into and projecting, normally, vertically through and from the slot and directly above the central portion of the said strip in alignment with the central longitudinal axis of said strip, substantially as and for the purposes set forth. 10
8. In a purse or bag frame, the combination, with a pair of frame-sections 1 and 2, said section 2 having lug-receiving holes, of a chambered bead-strip provided with lugs 8 arranged in said holes in the frame-section 2 and bent over against the under surface of said frame-section, said strip having a longitudinally-extending and centrally-disposed slot in its upper surface and inwardly-extending supporting-lugs connected with said strip, a holding-catch mechanism supported on said supporting-lugs, and an upwardly-projecting finger-piece on said mechanism extending into and projecting, normally, vertically through and from the slot and directly above the central portion of the said strip in alignment with the central longitudinal axis of said strip, said catch mechanism, comprising, a spring-actuated catch-plate and a holding-catch 17, and holding-lugs on the other frame-section 1 adapted to be brought in holding engagement with said catch 17, substantially as and for the purposes set forth. 15
9. In a purse or bag frame, the herein-described holding-catch device, consisting, essentially, of a catch-plate, a finger-piece extending in an upward direction from said catch-plate, a downwardly-extending holding-catch on said plate, a spring, supporting members 23 on which said spring rests, and holding-lugs encircling portions of said spring, substantially as and for the purposes set forth. 20
10. In a purse or bag frame, the herein-described holding-catch device, consisting, essentially, of a catch-plate, a finger-piece extending in an upward direction from said catch-plate, a downwardly-extending holding-catch on said plate, a spring, supporting members 23 on which said spring rests, and holding-lugs encircling portions of said spring, the said finger-piece being provided with a slot, and said spring having an angular portion extending into said slot, substantially as and for the purposes set forth. 25
11. In a purse or bag frame, the combination, with the frame-sections, of a chambered bead-strip on one of said frame-sections, provided with openings 10 for the insertion of holding-lugs, and a catch device in the chamber of said strip, consisting, of a catch-plate, a finger-piece extending in an upward direction from said catch-plate, a downwardly-extending holding-catch 17 directly back of said openings 10, a spring, supporting members 23 on which said spring rests, and lugs on said catch-plate encircling portions of said spring, and holding-lugs on the other frame-section adapted to enter said openings 10 and engage with said holding-catch 17, substantially as and for the purposes set forth. 30
12. In a purse or bag frame, the combination, with the frame-sections, of a chambered bead-strip on one of said frame-sections, provided with openings 10 for the insertion of holding-lugs, and a catch device in the chamber of said strip, consisting, of a catch-plate, a finger-piece extending in an upward direction from said catch-plate, a downwardly-extending holding-catch 17 directly back of said openings 10, a spring, supporting members 23 on which said spring rests, and lugs on said catch-plate encircling portions of said spring, the said finger-piece being provided with a slot and said spring having an angular portion extending into said slot, and holding-lugs on the other frame-section adapted to enter said openings 10 and engage with said holding-catch 17, substantially as and for the purposes set forth. 35
13. In a purse or bag frame, the combination, with the frame-sections, of a chambered bead-strip on one of said frame-sections, provided with openings 10 for the insertion of holding-lugs, and inwardly-extending supporting-lugs 11 on said strip, and a catch device in the chamber of said strip, consisting, of a catch-plate resting directly upon the said supporting-lugs 11, a finger-piece extending in an upward direction from said catch-plate, a downwardly-extending holding-catch 17 directly back of said openings 10, a spring, supporting members 23 on which said spring rests, and lugs on said catch-plate encircling portions of said spring, and holding-lugs on the other frame-section adapted to enter said openings 10 and engage with said holding-catch 17, substantially as and for the purposes set forth. 40
14. In a purse or bag frame, the combina- 45

tion, with the frame-sections, of a chambered bead-strip on one of said frame-sections, provided with openings 10 for the insertion of holding-lugs, and inwardly-extending supporting-lugs 11 on said strip, and a catch device in the chamber of said strip, consisting, of a catch-plate resting directly upon the said supporting-lugs 11, a finger-piece extending in an upward direction from said catch-plate, 5 a downwardly-extending holding-catch 17 directly back of said openings 10, a spring, supporting members 23 on which said spring rests, and lugs on said catch-plate encircling portions of said spring, the said finger-piece

being provided with a slot and said spring 15 having an angular portion extending into said slot, and holding-lugs on the other frame-section adapted to enter said openings 10 and engage with said holding-catch 17, substantially as and for the purposes set forth. 20

In testimony that I claim the invention set forth above I have hereunto set my hand this 19th day of April, 1901.

ALBERT F. FULLER.
